HOSIERY

Erwin Ruckel, Richmond Hill, N. Y., assignor to
 Louis Hirsch Textile Machines, Inc., New York,
 N. Y., a corporation of New York

Application May 7, 1938, Serial No. 206,512

2 Claims. (Cl. 66—172)

This invention relates to a new and useful improvement in hosiery, particularly in full-fashioned flat knit hosiery, and in the method of knitting it. A particular object of the invention is the improvement and simplification of the topping operation preceding the joining of the heel tabs and side sole portions of hosiery knit on single-unit machines, and of those in which a legger is employed to knit the legs and feet as a unit.

In knitting a stocking upon a single-unit flat knitting machine the usual procedure is to knit the leg and high heel splices and then to knit the heel tabs, the knitting of the instep being suspended meanwhile. When the heel tabs are completed the knitting of the foot and sole is in order, but it is customary to first knit a few sole ravelling courses to prevent ravelling of the initial sole courses when the completed stocking blank is removed from the knitting machine, and to assist in topping onto the looping machine by which the heels and sole portions are joined.

When performing this topping operation it is essential that every one of the sinker loops of the first course of the sole be topped onto its individual point, a difficult operation and one extremely trying to the eye-sight. By this invention this operation is greatly simplified, and the danger of runs developing from dropped sinker loops eliminated.

When a legger is employed to knit the leg and foot of a stocking as a unit, the knitting of the instep and sole portions of the foot is begun immediately after the leg and high heel splices have been completed. However, since the high heels must be severed later from the sole portions so that the heel tabs and sole portions can be looped together, it is customary to knit a few courses, usually unreinforced, between the reinforced high heels and the reinforced sole (called intermediate or severing courses) to serve as a guide for topping and cutting. To avoid runs the topping operation must be performed before cutting. The needle loops of the last course of the high heel and the sinker loops of the first course of the sole portions must be topped upon the two rows of topping points of a double topping stand, and since the two courses of loops are separated by only the two or three intermediate courses, the topping of the sinker loops is not only a difficult and slow operation, but is likely to be imperfectly done by even a skilled and careful operator. By this invention the sole portions of the fabric are rendered run-proof even against imperfect topping.

The forms of the invention selected for description herein are illustrated by the drawings, of which—

Figure 1 is a diagrammatic illustration of a part of the sole and instep portions of the foot 5 of a stocking assumed to have been knit upon a single unit flat knitting machine after the completion of the leg and high heels and heel tabs.

Figure 2 is a diagrammatic illustration of the adjacent parts of the leg and foot of a stocking assumed to have been knit as a unit upon a standard legger;

Figure 3 is an enlarged diagrammatic illustration of a part of the fabric found in the latter 15 of these blanks.

As illustrated by Figure 1 and as generally described above, the knitting upon a single unit machine of the instep and sole portions 1 and 2, respectively, of the foot has been preceded by the knitting of sole-ravelling courses 3. The first 20 course of these sole portions is rendered run-proof by the inclusion of picot 4 in the last courses of the ravelling course sections. Then the knitting of the instep and the sole portions of the foot is begun and carried to completion. 25 When the heel tabs and the first course of the sole portions are topped onto the looping machine, the latter may be topped by simply forcing the first course onto the topping points without making any particular effort to see that all of 30 the sinker loops are topped. If some are missed, no harm can follow, since the preceding courses of run-proofing construction prevent the starting of runs at this edge of the sole portions. In fact, it is immaterial if some of the loops 35 topped are needle loops and some sinker loops, or if part of the loops are in one course and part in the next course, provided, that none of them are on the wrong side of the run-proof courses 4.

Figure 2 illustrates adjacent portions of the 40 leg and foot fabric of a stocking blank knit as a unit on a standard legger. As will be understood by those skilled in the art, the high heels 5 and the sole portions 6 are temporarily connected by a few intermediate courses 7 usually 45 unreinforced, which serve as a guide for subsequent topping and severing. When the knitting of the foot has been completed, it has been necessary heretofore to top onto a double topping stand first the needle loops of the last course 8 of the 50 high heels and then the sinker loops of the first course 9 of the sole portions. Since these two courses are very close together and are joined by the intermediate severing courses such topping is an extremely difficult operation. 55

The fabric is now cut along the intermediate severing courses 7 and the heel tabs knit onto the ends of the high heels and ravelling courses simultaneously knit on the sole portions, or, if 5 another method is followed, the heel tabs are joined to the sole portions, course by course, as the heel tabs are knit.

To simplify the above-described topping operation a picot 10 is made in the courses immediately preceding the first course 9 of the sole portions. This will prevent runs starting at this edge of the side sole portions after the fabric is severed along the intermediate courses. Because of this, it is only necessary to top the needle loops 15 of the last course of the high heels upon one row of the topping points of the double topping stand, and then to simply push the first course after the locking courses of the sole portions upon the other row of points, making no effort to top each 20 sinker loop as has been essential heretofore. As in the other case, it is not even important that all of the loops topped should be in the same course. Part may be in one course and part in another, provided all of them are on the right side of the 25 run-proofing courses.

Also, because of the presence of the run-proofing course, a single row topping stand may be used, if desired, the needle loops of the last course of the high heels being topped, the high heels 30 then severed from the sole portions along the intermediate courses and the heel tabs knit. The sole portions, although not topped, cannot ravel and may later be pushed onto the points of the looping machine without regard to what loops are 35 actually placed on the points.

In this way, the topping operation is greatly simplified and speeded up, and rendered more

certain, and the strain upon the eye-sight of the operator greatly reduced. Although, technically speaking, the topping of the sole portions may be less perfectly done, by this method the imperfections are not observable except by the closest 5 inspection.

Although picotting has been shown and described as the means for rendering the sole portions run-proof, any other suitable run-proofing loop arrangement may be substituted in whatever 10 courses necessary to run-proof the desired courses. This has been designated herein as the first course of the sole portions, but it will be understood that the entire sole portions are in fact run-proofed and that any course beyond the 15 run-proofed courses may be topped and looped or otherwise joined to the heel tabs in the manner described.

I claim:

1. A heelless stocking blank having leg, high 20 heel and foot portions knit as a unit, said foot portions including sole portions connected to the corresponding ends of the high heel portions by one or more severing courses followed by courses of run-stop construction, said last-mentioned 25 run-stop courses constituting in the finished stocking a loose selvage anterior to said sole portions.

2. The method of knitting a heelless stocking blank which consists of knitting the leg, high 30 heels and foot portions as a unit, said foot portions including two sole portions one below each high heel and spaced therefrom but connected thereto by one or more severing courses followed by courses of non-run construction. 35

ERWIN RUCKEL.
